Alexander Doman Inventor
By his Attorney
Philip C. Reck

UNITED STATES PATENT OFFICE.

ALEXANDER DOMAN, OF NEW YORK, N. Y., ASSIGNOR OF ONE-HALF TO NATHAN M. ROSEN, OF NEW YORK, N. Y.

DESIGN FOR A HAT-LINING.

57,595.

Specification for Design. **Patented Apr. 26, 1921.**

Application filed January 3, 1921. Serial No. 434,814. Term of patent 14 years.

To all whom it may concern:

Be it known that I, ALEXANDER DOMAN, a citizen of the United States, residing in the borough and county of the Bronx, in the city and State of New York, have invented a new, original, and ornamental Design for Hat-Linings, of which the following is a specification, reference being had to the accompanying drawing, forming a part thereof.

The figure is a plan view of a hat-lining showing my new design.

I claim:

The ornamental design for a hat-lining as shown.

ALEXANDER DOMAN.

Witnesses:

DAN C. BEERMAN,
LOUIS FORTGANG.
